UNITED STATES PATENT OFFICE.

JOHN W. JAYCOX, OF ELKHORN, KANSAS.

BARREL-HOOP.

No. 800,583.

Specification of Letters Patent.

Patented Sept. 26, 1905.

Application filed December 12, 1904. Serial No. 236,570.

To all whom it may concern:

Be it known that I, JOHN W. JAYCOX, a citizen of the United States, residing at Elkhorn, in the county of Ellsworth and State of Kansas, 5 have invented new and useful Improvements in Barrel-Hoops, of which the following is a specification.

This invention has relation to barrel-hoops; and it consists in the novel construction and 10 arrangement of its parts, as hereinafter shown and described.

The object of the invention is to provide a metallic hoop which may be easily and readily adjusted and applied to barrels, or the same 15 hoop may also be applied to casks, boxes, and other receptacles.

The hoop consists of a wire strand having fixed at one end a perforated plate and being attached at its other end to the intermediate 20 portion of a pivoted bail, said bail in turn being pivoted between ears projecting from a plate which is adapted to be attached to one of the barrel-staves. In applying the hoop the plate having the ears is secured to the 25 barrel and the wire strand is carried around the barrel and the perforated plate is attached to the ear-plate in such manner as to leave the wire slack. The bail is then turned upon its pivot in such manner as to take up the slack 30 in the wire and to carry the wire beyond the pivotal point of the bail, so that the strain will come upon the free end of the bail, or nearer the barrel than the pivotal points of the bail, whereby the said bail will be held in 35 such position.

In the accompanying drawings, Figure 1 is a side elevation of the upper portion of the barrel, showing the hoops applied thereto. Fig. 2 is a horizontal sectional view of a portion 40 of the barrel and the bail; and Fig. 3 is a perspective view of the ends of the wire strand, the plates, and the bail.

The hoop consists of the wire strand 1, to one end of which is attached a perforated 45 plate 2. The other end of said wire strand 1 is attached to the intermediate portion 3 of the bail 4. The ends of the said bail 4 are pivoted in the ears 5, carried by the plate 6. The said plate 6 is provided with suitable per- 50 forations 7, through which nails may be inserted for securing the said plate to the barrel or receptacle. The bail 4 is slightly curved along its longitudinal axis, as indicated above in the solid and dotted lines of Fig. 2 of the 55 drawings. The bail 4 is preferably made of

a piece of heavy wire or metal rod, and its ends are pivoted in the ears 5 at some little distance out or away from the plate 6.

The hoop is applied to the barrel or receptacle as follows: The plate 6 is secured to the 60 barrel, and the wire strand 1 is carried around the barrel, and a nail 8 (see Fig. 2) is inserted through one of the perforations 9 of the plate 2, which fits between the ears 5 and also through the corresponding perforation 65 10 in the plate 6. The plate 2 is so adjusted as to leave the wire strand 1 slack. The bail 4 is then swung around upon its pivotal points, which takes up the slack in the wire strand 1, and the free end of said bail is carried in close to the side of the barrel or receptacle in a manner as illustrated in Fig. 2. In doing so the wire strand 1 passes between the pivoted ends of the bail 4 and fits closely around the barrel. The strain thus exerted 75 by the wire strand 1 is such as to keep the bail in the closed position above described, as the said bail is slightly curved along its longitudinal axis and the pivoted end of the bail is set out and away from the barrel. To remove the hoop, an implement is inserted under the other end of the bail 4, and it is swung out and around upon its pivotal points when the wire strand 1 becomes slack and may be 80 easily and readily removed. 85

It will be observed that when the bail 4 is swung with relation to the plate 6 to draw the strand 1 tight the free end of the said bail, to which the end of the said strand is attached, passes beyond the plate 6. The ad- 90 vantage of this construction is that the intermediate portion 3 of the said bail 4 may be made relatively long or of substantially the same length as the width of the plate 6. Thus the ends of the bail are not inclined toward a 95 point at the intermediate portion 3, and when the bail is swung the strand 1 will not be liable to slip from the said portion 3 along the sides of the bail, as would be the case if the sides of the bail were inclined toward a point 100 at the intermediate portion 3.

Having described my invention, what I claim as new, and desire to secure by Letters Patent, is—

1. A hoop consisting of a strand, a perfo- 105 rated plate attached to one end thereof, a second plate having outwardly-extending ears, said first perforated plate adapted to slip between the ears of the second said plate, and a means for securing the two said plates to- 110

gether, a bail pivoted between the ears of the second said plate, and having the other end of the strand attached to the free end thereof.

2. A hoop consisting of a strand, having at 5 one end thereof a means for securing the same, a plate having outwardly-extending ears, a bail pivoted between said ears and having the other end of the strand attached to its free end, said bail being so mounted with relation

to the plate having ears that when it is swung ¹⁰ to draw the strand taut, the free end of the bail passes beyond the said plate.

In testimony whereof I affix my signature in presence of two subscribing witnesses.

JOHN W. JAYCOX.
